TIRE

James W. Pond, Doylestown, Ohio, assignor to The
B. F. Goodrich Company, New York, N.Y., a corpora-
tion of New York

Filed Sept. 9, 1966, Ser. No. 3,794

Term of patent 14 years

(Cl. D90—20)

FIG. 1

FIG. 2

FIG. 1 is a fragmentary perspective view of a tire showing my new design, it being understood that the portions appearing in full lines are repeated throughout the entire circumference of the tire, the opposite wall of the tire being like the portion of the wall shown in full lines; and

FIG. 2 is an enlarged fragmentary plan view of the tire shown in FIG. 1.

The dominant features of the design reside in those portions shown in full lines.

I claim:

The ornamental design for a tire, substantially as shown and described.
